Arthur B. Jenkins,
ATTORNEY.

UNITED STATES PATENT OFFICE.

GEORGE KINGHORN, OF ROCKYHILL, CONNECTICUT.

POCKET DOOR-LOCK.

1,266,689.

Specification of Letters Patent. Patented May 21, 1918.

Application filed June 11, 1917. Serial No. 173,932.

To all whom it may concern:

Be it known that I, GEORGE KINGHORN, a citizen of the United States, and a resident of Rockyhill, in the county of Hartford and 5 State of Connecticut, have invented a new and Improved Pocket Door-Lock, of which the following is a specification.

My invention relates to the class of devices that may be carried in the pocket and 10 that may be used as an extra precaution in locking a door, especially on the inside, and an object of my invention, among others, is to provide a lock of this class that may be readily placed between the edge of a door 15 when closed and the door jamb, and one in which the locking members may be certainly engaged with and disengaged from each other.

One form of my improved lock is illus- 20 trated in the drawings herein in which:

Figure 1 is a face view of my improved lock.

Fig. 2 is a view similar to Fig. 1, but showing the locking bars extended from the 25 case.

Fig. 3 is a view in horizontal section through a portion of a door and a jamb showing my improved lock in position before the door is closed.

30 Fig. 4 is a view similar to Fig. 3, showing the door closed and the lock case and other parts in their locked position.

Fig. 5 is a view in cross section on plane denoted by dotted line 5—5 of Fig. 1.

35 Fig. 6 is an end view of my improved lock.

In the accompanying drawings the numeral 5 indicates a case that is preferably of thin metal of flat, tubular form and thin 40 as compared with its length and width. This case is preferably tapered in form, although this is not essential to my invention. Locking bar actuating grooves 6 are formed in pairs, on a member or members of the 45 structure, in the device shown herein these grooves being formed in the case and preferably one groove of each pair being located opposite a groove of the other pair in opposite walls of the case. The members of 50 each pair of grooves are angularly arranged with respect to each other, as shown in dotted lines in Fig. 1 of the drawings, this arrangement being for the purpose of causing locking bars, hereinafter described, to 55 be moved into engagement with, and out of engagement from each other, and I, there-

fore, contemplate many different arrangements of these grooves that will effect the desired purpose, and it will also be evident that the grooves may extend entirely through 60 the walls of the case.

Locking bars 7—8 extend into the case 5 and project from one end at least of said case. These locking bars are formed of very thin metal and they are placed with their 65 flat faces in the same plane. Actuating pins 9 project from the faces of the bars, there being preferably as many of these pins as there are grooves 6, the pins entering the 70 grooves and serving the purpose of separating the bars, or for drawing them together as the case is moved lengthwise along the bars. The meeting edges of the locking bars are formed with inter-engaging teeth 10, so that as the bars are drawn together, in the 75 manner hereinabove described, they will lock against relative lengthwise movement, and this locking engagement will exist when the bars are within the case to the greatest extent and as shown in Fig. 1 of the draw- 80 ings.

Each bar is provided with a locking dog 11 extending from one face and at or near the end of said bar. The dog on each bar extends across the line of separation between 85 the bars and overlying a face of the opposite bar, each dog being cut away as at 12 to receive the edge of the bar opposite to that on which it is located, and thus permitting the bars to be located in the same plane. 90 This arrangement not only gives a maximum strength to each of the dogs, but each dog supports a locking bar against movement from a force that would be caused in an effort to open a door secured by my improved 95 lock, such force being caused by reason of the beveled faces on the dogs that are shaped to conform to the beveled end of a latch 14 and the bottom of a recess in a keeper 15 in the door jamb. These dogs are straight on 100 that side opposite the bevel, that is, this side of each dog is substantially perpendicular to the face of the locking bar on which it is supported. The beveled side of each dog has two sloping surfaces, the one extending 105 from the point of each dog and denoted by the numeral 13 being steeper than the beveled face 16 located at the base of the dog. The angle from the point 17 of each dog to the base is substantially the same as the angle of 110 inclination of the end of the latch and the bottom of the recess hereinbefore referred to,

and the steeper beveled face 13 is provided for the purpose of enabling the dog to be driven into a door jamb and the edge of a door, when occasion may require, and in 5 cases where there are no latch openings or keeper recesses, or where such may not be applicable to receive the dogs. In order to increase the driving qualities of the dogs there are recesses as at 18 to provide cutting edges 19 that will be an aid to the dogs in penetrating wood when they are driven in. As an extra precaution to prevent unwarranted unlocking action of the locking bars, a hole 20 is formed through the case and a hole 21 through the locking bar, within 15 which hole a pin may be inserted to absolutely prevent an endwise movement of the case and bars with respect to each other.

This structure of the blades and dogs enables me to obtain the great strength that is required in a structure of this class, and at the same time to provide blades thin enough to serve the purpose desired, as the blades and dogs may be drop-forged, thus providing 20 not only a cheap construction, but one of extreme strength and durability.

In accordance with the provisions of the patent statutes, I have described the principle of operation of my invention, together 30 with the apparatus which I now consider to represent the best embodiment thereof; but I desire to have it understood that the apparatus shown is only illustrative, and that the invention can be carried out by other 35 means.

I claim:

1. A door fastener including a case, locking bars projecting from one end of the case and movable lengthwise therein, interengaging locking members on the meeting edges 40 of the locking bars, and means upon the case and locking bars and independent of said locking members to cause the bars to be separated by reason of their lengthwise 45 movement.

2. A door fastener including a case, locking bars projecting from one end of the case and movable lengthwise therein, said bars having interengaging locking members 50 to prevent endwise movement one independently of the other, and means upon the case and locking bars to actuate the latter and including guideways angularly arranged with respect to each other on one part to 55 receive actuating pins from the opposite part.

3. A door fastener including a case, locking bars projecting from one end of the case and movable lengthwise therein, said bars having interengaging locking members on 60 the meeting edges thereof, and locking pins

projecting from the locking bars into angularly arranged grooves in said case to move the bars toward and from each other.

4. A door fastener including a flat, thin case, flat locking bars projecting from one end of the case and located with their flat faces in the same plane, dogs located on the ends of the bars, each dog projecting over and resting against the face of the bar opposite to that on which it is located when the dogs are substantially in lateral alinement, and means for locking the bars against relative lengthwise movement.

5. A door fastener including a flat, thin case, flat locking bars projecting from one end of the case and movable lengthwise therein, said bars being located with their flat faces in the same plane, dogs projecting from opposite faces of the bars, each dog being undercut to overlie, rest against, and receive the end of the bar opposite to the one on which it is located when the dogs are substantially in lateral alinement, and means for locking the bars against relative 85 endwise movement.

6. A door fastener including a case, locking bars projecting from one end of the case and movable lengthwise therein, said bars having toothed interengaging meeting edges, 90 dogs projecting in opposite directions from the face of the bars, each dog being undercut to overlie and receive the edge of the bar opposite to the one on which it is located, and interengaging means between the 95 bars and case to cause the bars to be moved toward and from each other as they are moved lengthwise in the case.

7. A door fastener including a flat case, flat locking bars projecting from the end of the case and movable lengthwise therein, interengaging pins and grooves upon the bars and case to cause the bars to move toward and from each other by reason of the endwise movement of the case along the bars, 100 interengaging locking teeth on the meeting edges of the bars, and dogs projecting from opposite faces of the bars, each dog being undercut to receive and overlie the bar opposite to that on which it is located.

8. A door fastener including a flat thin case, flat locking bars projecting from one end of the case and located with their flat faces in the same plane, dogs located on the ends of the bars, each dog projecting over 110 and resting against the face of the bar opposite to that on which it is located, said bars and dogs thereon being duplicates each of the other, and means for locking the bars against relative endwise movement.

GEORGE KINGHORN.
